UNITED STATES PATENT OFFICE

RALPH R. HALL, OF CHICAGO, ILLINOIS

SECTIONAL WARP BEAM

Application filed June 25, 1929. Serial No. 373,631.

My invention relates to warp beams for looms, and in some of its general objects aims to provide a warp beam which will prevent a tangling of the warp threads, which will readily permit a separate tensioning of different sections of the warp, and which will greatly facilitate both the widening and the narrowing of the warp whenever this is desired.

In foot looms, the warp threads are usually wound on a single beam of considerable length, thereby requiring considerable time for any careful winding. Even with such tedious winding, it is difficult to keep the proper threads side by side; so that in practice, some of the threads usually tangle and tear, thereby requiring time for joining the ends of the torn threads.

Moreover, when threads of different colors are used for different sections of the warp, the varying effect of the several dyes on the threads causes these to tension differently, thereby increasing the difficulty of operating the loom. So also, the usual single-piece warp beam does not permit a ready substitution of threads of other colors for any section of the warp in case this is desired as the work progresses. Furthermore, since the warp beam customarily is initially wound with an excessive length of thread in proportion to that required for the proposed fabric, considerable time has to be spent in unwinding the surplus from the warp before this beam can be rewound to afford a new arrangement of the variously colored sections of the warp.

My present invention aims to overcome all of the above recited objections by providing separate and interchangeable spools on each of which the thread for a single warp section is wound, by providing simple means for rotating all of these warp spools from the usual beam-rotating sprocket, by providing simple means whereby any spool may be released from the driving connection to permit the threads on each spool to be tensioned independently of the threads on the other spools, and by providing the spools with relatively interlocking means arranged for permitting considerable variations in the readjustment of the tensioning. Moreover, my invention

aims to provide simple means for normally holding the spools and the driving sprocket in relatively interlocked disposition, and for detaching these means to permit a separation of the spools when the tensioning of the threads is to be adjusted.

Still further and also more detailed objects will appear from the following specification and from the accompanying drawings, in which

Fig. 1 is a fragmentary plan view of the let-off end portion of a loom equipped with my invention.

Fig. 2 is a side elevation, taken from the line 2—2 of Fig. 1.

Fig. 3 is a vertical section, taken from the line 3—3 of Fig. 1.

Fig. 4 is a fragmentary vertical section taken through the axis of the warp beam, along the line 4—4 of Fig. 1.

Fig. 5 is a perspective view of the detachable spacer, the removal of which permits spools of my warp beam to be slid out of interlocking engagement with other spools.

In the illustrated embodiment, each side frame 1 of the loom carries bearings 2 fastened to that frame by detachable screws 3. Spanning these bearings and journaled in them is a shaft 5 which extends successively through the hubs 6 of the warp spools and through the bore of the driving sprocket 13, this sprocket being normally spaced from the adjacent bearing 2 by a removable spacer 7 which is pictured separately in Fig. 5. To reduce the friction I may interpose a washer 8 between the spacer and the adjacent bearing, and may likewise interpose a second washer 8A between the companion bearing 2A and the warp spool adjacent to the latter bearing.

Each warp spool comprises two washer-like ends 9, desirably made of fibre and fastened to the ends of a hub 6, and the entire spools desirably are counterparts of each other. Driven into one end of each hub 6 parallel to the axis of the hub and projecting beyond that hub is a latching pin 10, while the other end of each hub has at least one (and desirably more) bores 11 spaced from the axis of the hub by the same distance as the latching pin 10, each of these bores being of such a

size that the projecting part of the pin 10 on an adjacent spool hub can socket in that bore. These bores are shown in Fig. 3 as four in number and as uniformly spaced. The 5 sprocket 13 also has bore 11 of similar size and similar spacing from the axis of the sprocket, extending into the latter from the side of the sprocket which is adjacent to the spools.

10 To connect the driving sprocket 13 operatively with the shaft 5, I desirably provide this sprocket with a hub 14 (Fig. 1) extending toward the adjacent side frame member 1, which hub has a recess 15 fitting an inwardly directed projection 16 on the spacer 7. Then I secure this spacer to the shaft 5 by a bolt 17 extending transversely of the shaft 15 through both the shaft and the projection 16.

With the let-off end of a loom thus arranged, the threads 18 for each warp section are wound on the separate spools before the spools are slipped on the shaft. Since the number of parallel threads on each spool is only a small fraction of the total number of 25 warp threads, this winding is easily effected with uniformity for the threads and with no crossing of the threads. Moreover, the spools can be rotated by a motor-driven or foot-driven spindle during the winding, thereby 30 reducing the required time.

When the assembly is completed as in Fig. 1, each spool is interlocked by its projecting latch pin 10 with the spool at its left, and the spool at the extreme left is similarly interlocked with the sprocket 13. Consequently, the movement of the sprocket by the usual drive chain 19 will rotate all of the spools conjointly, thus feeding the threads just as if they had been wound on the usual single-piece warp beam. However, the warp threads 40 on each spool are initially spaced from those on each adjacent spool by the thickness of two of the spool ends 9, thereby still further reducing the chance of any entangling of the 45 threads.

If the several (spool-wide) sections of the warp threads tension unevenly during the 50 operation of the loom, the bolt 17 is detached, thereby permitting the spacer (of Fig. 5) to be removed by sliding it off the shaft radially 55 of the latter. This leaves a free space between the washer 8 and the hub 14 of the sprocket, corresponding to the thickness of the spacer 7, and the sprocket 13 can then be slid over to the same extent (to the left in Fig. 1) against the washer 8. By doing this, and by preferably 60 making the thickness of the spacer 7 several times the length of the projecting portions of the latch pins 11, I provide room for 65 spacing any desired spool freely from adjacent spools, thus permitting any spool to be rotated in either direction for increasing or decreasing the tension of the threads fed it.

For example, if the user of the loom finds 70 65 that the warp threads fed from a given spool

are more slack than those supplied by the other spools, he detaches the spacer member 7, slides the sprocket away from the spools, and slides the spools so as to release the said slack-thread spool from its interlocking with 75 the spools between which it is interposed. He then can rotate the slack-thread spool to tension its threads in substantial harmony with the threads leading from the adjacent spools, and to such a degree depending on the number of sockets or bores 11 in each spool end, 80 after which he again slides all spools and the sprocket into interlocking assembly with each other and replaces the spacer. If the tension of threads from one spool is greater than that from the adjacent spools, the adjustment is similarly made by rotating the higher tensioned spool in the opposite or thread-slackening direction. Since this can all be done 85 without removing the warp beam from its bearings and without disturbing the tension of the threads leading from other spools, the entire time required for such an equalizing of the tension of threads on different spools is only a small fraction of that required with 90 the provisions heretofore in use.

When the tensioning has thus been made approximately uniform for the threads from all of the spools, each spool is again interlocked with the adjacent ones, after which 95 the sprocket is slid back into interlocking engagement with the pin on the spool adjacent to it, the spacer is slipped back into position, and the bolt 17 is again attached. By providing a plurality of counterpart sockets 100 or bores 11 in each spool, I can readily secure a suitably fine adjustment of the tensioning, so that I eliminate the need of weights, springs or counterbalances as tension equalizers.

When the warp is to be narrowed, the threads fed from certain of the spools are severed and these spools can then be left to rotate freely. Then when the warp is to be widened, threads fed from previously idle spools 110 are added to the warp, so that I greatly facilitate such changes in the width of the fabric, as I eliminate the heretofore required entire rewarping of the loom.

By detaching the bearings 3 from the loom 115 sides and likewise detaching the spacer and the sprocket from the shaft, I permit part or all of the spools to be slid off the shaft, so that these can readily be replaced by other spools carrying either duplicate or different 120 threads.

Since the needed spools are cheaply manufactured, the loom user can carry a supply of spools wound with various kinds and colors of threads, without incurring any large investment, thereby enabling him to proceed expeditiously with a variety of work. Moreover, by using a row of such interlocking spools instead of a single warp beam, I eliminate the heretofore required (and undesir- 125 130

ably tedious) winding of a warp chain, so that I add greatly to the enjoyment of a loom by amateurs.

In practice, I desirably construct my spools 5 with an inch spacing between the two ends of each spool (which facilitates the work, since weaving is usually figured according to the number of threads per inch) and correspondingly proportion the distance between the 10 bearings for the shaft.

By fastening the sprocket to the shaft and interlocking the sprocket with the row of consecutively interlocking spools, I cause the shaft to rotate with the spools, so that there 15 is no wear on the bores of the spool hubs, thus permitting me to use wooden hubs for the spools.

However, I do not wish to be limited in this respect, nor to the use of my invention 20 in connection with foot looms. Nor do I wish to be limited to other details of the construction and arrangement above described, since many changes might be made without departing either from the spirit of my invention or 25 from the appended claims.

I claim as my invention:

1. In a loom, a shaft; a row of warp-carrying spools slidably carried by the shaft, each spool including a hub and two ends, and each 30 spool having one end abutting against the end of an adjacent spool; each spool having a socketing bore in the right-hand end of its hub and having in its left-hand end a pin projecting beyond the hub parallel to the axis of 35 the spool and formed for entering the socketing bore in the next spool at the left of the aforesaid spool; a driving sprocket adjacent to the left end of the row of spools and slidably carried by the shaft, the sprocket having 40 a socketing bore normally entered by the pin projecting from the left-hand end spool of the row, means adjacent to the right-hand end spool for preventing a sliding of the last named spool toward the right, and releasable 45 means associated with the sprocket to prevent a sliding of the sprocket toward the left, the releasable means being of greater dimension longitudinally of the shaft than the distance to which the pin on any spool projects 50 beyond the hub of that spool.

2. In a loom, a shaft; a row of warp-carrying spools rotatable upon and slidably carried by the shaft; means associated with each spool for interlocking the spool against rotation with respect to an adjacent spool, the 55 said means being released by sliding one spool away from an adjacent spool; means adjacent to one end of the row of spools for limiting the row of spools from sliding toward that end, a sprocket slidable on the shaft and interlocked against rotation with the spool at the other end of the row, a stop near and outward of the sprocket, and a detachable spacer normally interposed between 60 the stop and the sprocket, and normally hold-

ing the sprocket interlocked with the last named spool, the spacer being detachable by a movement radially of the shaft without removing the spools or sprocket from the shaft.

3. A loom part assembly as per claim 2, 70 in which the sprocket has a recess and in which the spacer has a projection normally housed by the recess to prevent rotation of the sprocket with respect to the spacer, in combination with detachable means for 75 fastening the spacer to the shaft.

4. A loom part assembly as per claim 2, 80 in which the sprocket has a recess and in which the spacer has a projection normally housed by the recess to prevent rotation of 85 the sprocket with respect to the spacer, in combination with a detachable fastening member extending both through the shaft and through the said projection on the spacer.

5. In a loom, two rigidly spaced side members, a shaft spanning and journaled in the two side members, a row of warp-carrying spools slidably carried by the shaft between the two side members, a driving member mounted on the shaft between one side member 90 and one end of the row of spools; the driving member being formed for interlocking against rotation with the spool adjacent to it, and each spool being formed for interlocking against rotation with an adjacent 95 spool, the joint length of the row of spools and of the driving member being less than the spacing between the said side members, and a detachable spacer interposed between the driving member and the adjacent side member for holding the driving member and the spools in their said interlocked disposition.

6. In a warp beam for a loom, a shaft; a row of warp-carrying spools slidably carried 105 by and rotatable upon the shaft, each spool having a projection disposed for interlocking in any one of a plurality of rotationally different positions with the adjacent spool to prevent relative rotation of the spools, 110 and means interlocking with the spool at one end of the said row for imparting rotation to that spool.

7. In a warp beam for a loom, a shaft; a row of warp-carrying spools slidably carried by and rotatable upon the shaft, each spool having a projection disposed for interlocking in any one of a plurality of rotationally different positions with the adjacent 120 spool to prevent relative rotation of the spools, a sprocket slidable on the shaft and interlocked with the spool at one end of the said row for imparting rotation to that spool by means releasable upon a sliding of the sprocket away from that end spool, and 125 releasable means normally holding the sprocket in interlocking relation to the said end spool.

8. In a warp beam for a loom, a shaft, a row of counterpart warp-carrying spools 130

slidably carried by and rotatable upon the shaft, each spool having a pin projecting from one end of the spool and having at its other end a socket entered by the pin on an adjacent spool, and means associated with an end spool of the said row for rotating the said end spool.

9. In a warp beam for a loom, a shaft, a row of counterpart warp-carrying spools slidably carried by the shaft; each spool having a pin projecting from one end of the spool and having at its other end a plurality of sockets spaced circumferentially of the spool, each socket being adapted to be entered by the pin on an adjacent spool, and means associated with one of the spools for imparting rotation to the last named spool.

Signed at Chicago, Illinois, June 20th, 1929.
